UNITED STATES PATENT OFFICE.

ORION EUGENE KENT, OF GRAND RAPIDS, MICHIGAN.

MANDREL.

Application filed February 28, 1922. Serial No. 540,068.

To all whom it may concern:

Be it known that I, ORION EUGENE KENT, a citizen of the United States, residing at Grand Rapids, in the county of Kent, State 5 of Michigan, have invented a new and useful Mandrel; and I do hereby declare the following to be a full, clear, and exact description of the invention, such as will enable others skilled in the art to which it 10 appertains to make and use the same.

The invention relates to mandrels, and has for its object to provide a device of this character comprising conically shaped members adapted to be forced into similarly 15 shaped chambers in sleeves of pulleys and jammed therein. Also to provide an elongated screw extending and threaded through one of the conically shaped members and having its end in abutting engagement with 20 the adjacent conically shaped member and forming means whereby said members may be forced apart for removing the same from the conically shaped chamber in which they are jammed.

With the above and other objects in view the invention resides in the combination and arrangement of parts as hereinafter set forth, shown in the drawings, described and claimed, it being understood that changes 30 in the precise embodiment of the invention may be made within the scope of what is claimed without departing from the spirit of the invention.

In the drawing:

Figure 1 is a front elevation of the mandrel, showing the same applied to the sleeves of a conventional form of pulley, said sleeves being broken away and shown in section.

Figure 2 is a longitudinal sectional view 40 through the mandrel.

Figure 3 is a vertical transverse sectional view through the mandrel taken on line 3—3 of Figure 2.

Referring to the drawings, the numeral 1 45 designates a pulley and 2 the hubs thereof. The hubs 2 are provided with conically shaped chambers 3, in which chambers the frusto conically shaped mandrel members 4 are received. Extending through the members 4 is a bolt 5 which is provided with a head 6 having a lug 7, which is received in the recess 8 of one of the frusto conically shaped members 4, thereby locking the bolt and last named member 4 together. The 55 end 9 of the bolt 5 is threaded and is provided with a nut 10. It will be seen that

after the frusto conically shaped members 4 have been placed in the chambers they may be tightly jammed in said chambers 3 by means of the nut 10 thereby holding the 60 pulley tightly. It has been found that conically shaped members 4 are tightly wedged and jammed in the chambers 3, therefore it is necessary to provide means for forcing the conically shaped members 4 away from each 65 other. To accomplish this result an elongated screw 11 is provided, which screw is threaded at 12 through one of the conically shaped members 4 and has its end 13 in engagement with the inner face 14 of the 70 other conically shaped member 4. It will be seen that by applying a wrench to the head 15 of the screw 11, that said screw may be threaded inwardly in such a manner that the conically shaped members 4 will be 75 forced away from each other, that is after the nut 10 has been loosened or removed.

From the above it will be seen that a mandrel is provided, which may be easily and quickly placed in position within tapered 80 chambers and jammed therein. Also that the conically shaped cones of the mandrel may be easily and quickly forced apart by the screw 11 thereby breaking the jam or frictional binding of the conically shaped 85 cones in the similarly shaped chambers 3 of the sleeves 2.

The invention having been set forth what is claimed as new and useful is:—

A mandrel comprising a threaded shaft, a 90 head carried by one end of said shaft, lugs carried by the head and overlying the adjacent end of the threaded shaft, a frusto-conically shaped member disposed on the shaft and having recesses for the reception 95 of the lugs, a second frusto conically shaped member disposed on the threaded shaft, a nut threaded on the shaft and adapted to force said last named frusto conically shaped member inwardly, and a screw threaded 100 through one of the conically shaped members and having its end in abutting engagement with the first mentioned conically shaped member.

In testimony whereof I have signed my 105 name to this specification in the presence of two subscribing witnesses.

ORION EUGENE KENT.
